U. A. MARGA

AUTOMATIC FIREARM

Filed March 21, 1921

Inventor

Uldarique Auguste Marga

By Lawrence Lawyer
Attorney.

UNITED STATES PATENT OFFICE.

ULDARIQUE AUGUSTE MARGA, OF DIEGHEM, BRUSSELS, BELGIUM.

AUTOMATIC FIREARM.

Application filed March 21, 1921. Serial No. 454,129.

To all whom it may concern:

Be it known that I, ULDARIQUE AUGUSTE MARGA, a subject of the King of Belgium, of Dieghem, Brussels, in the Kingdom of Belgium, have invented new and useful Improvements Relating to Automatic Firearms (for which I have filed application in Belgium March 19, 1920), of which the following is a specification.

10 This invention relates to automatic firearms and has reference to firearms of the kind in which the movable breech is bolted to the barrel during a certain time after the percussion of the cartridge and thus carries 15 the barrel with it in its recoil movement.

The object of the present invention is to ensure that the unbolting of the movable breech of the barrel will take place at the proper instant. This result is essentially 20 obtained by effecting on recoil a partial rotation of the barrel in order to thereby disengage said barrel of the breech block, when the latter has completed a portion only of its recoil movement.

25 In the following description the invention will be described as applied to an automatic fire arm in which the hammer is worked by a striker in form of a spring piston displaced for example obliquely with respect to the 30 path of the movable breech in the breech casing and at the same time serving to check the recoil motion of the movable breech by the pressure it exerts on one of the lateral surfaces, after having been driven by the movable breech into its seat as described in Belgian Patent No. 196724. In a weapon of this 35 kind the firing mechanism can act directly on the striker piston to retain it until the time when the firing mechanism is pressed.

40 In the drawings which represent a form of construction of the invention by way of example, Fig. 1 is a longitudinal section through the axis of the fire arm. Fig. 2 is a view from above of the complete fire arm. Fig. 3 is an under side view of the movable breech separated. Figs. 4 and 5 are sections on the lines A B and C D of Fig. 3. Fig. 6 is a front view of the striker piston.

45 The breech casing 1, furnished in the ordinary way with an ejection opening 2 and an opening 3 for the introduction of the cartridges to which a magazine (not represented) is fitted, serves to guide the movable breech 4 and the barrel 5. The barrel 5 can 50 recoil in the breech casing against the action of a spring 6 and during this recoil, it per-

forms, for the purpose of unbolting, a rotary movement produced by a projection 7 on the barrel engaging in a helicoidal groove 8 of the breech casing. The movable breech 60 4 is provided with a hammer 9 continually drawn backwards by a spring 10; it also has a rod 11 running in a groove 12 of the breech-casing 1, and to which a retractile spring 13 is fixed on another part of the casing. 65

The weapon is represented in Fig. 1 in a closed position, before firing. Percussion is realized by a striker piston 14 guided in a cylinder 15 placed obliquely with regard to the path of the movable breech 4; this 70 striker is worked with a spring 16 and is kept in the cocked position by a firing mechanism in form of lever 17 the nose 18 of which engages in a hollow 20, made in the percussion surface 19 of the striker 14. 75 Pressure of the marksman's finger on the opposite extremity 21 of the firing mechanism releases the striker 14 which falls on the hammer. It is then that the movable breech is bolted to the barrel. For this purpose the barrel 5 has a rearward extension 22 provided with a retaining catch 23. There is a bolting button 24 in the movable breech 4 which can slide vertically in its seat. When the movable breech closes again, 80 this button 24 is driven downwards by the retaining catch 23, and takes the position given in Figs. 1 and 3. For this position, the hollow conical surface 25 formed in this button 24 blocks the opening of the passage 26 for the hammer point so that when the latter falls its point drives the button 24 upwards to engage with the retaining catch 23. 85 90

When the movable breech recoils, it draws away the barrel, until owing to rotation of the said barrel the parts occupy the position represented in Fig. 2. The button 24 then ceases to be engaged with the catch 23, so that the barrel stops and the movable breech 100 alone continues the recoil movement and the barrel is brought to the front by its spring the power of which is suitably regulated. During recoil, the movable breech 4 has driven into its seat the striker piston 14, but the higher surface 27 of the latter remains in contact with the bottom of the groove 28 of the movable breech and produces a checking of the recoil. The position of the striker 14 at this instant is the same as that 105 represented in Fig. 1 but the firing mechanism is still pressed by the finger of the 110

marksman. At the end of this recoil motion of the movable breech, the striker 14 is driven a little more deeply into its seat on the inclined plane 29 made in the groove 28. 5 Thus the projection 30 of the striker acts on the rod 31 integral with the firing mechanism 17 and brings the latter into the cocked position, in opposition to the action of the marksman's finger. The firing mechanism is 10 then kept in the cocked position by the spring 32. When the movable breech returns to the front, the striker rises slightly and is held by the firing mechanism. Of course by detaching the rod 31, the weapon 15 can be adapted for firing at intervals in sudden bursts.

It is to be noted that the recoil movement of the movable breech is further limited by the fact that the upper surface of the striker 20 is held by the bottom 33 of the groove 28. At the end of the recoil the front surface of the striker also acts on an ejector 34.

It must be noted that unbolting could also be obtained in various other manners. 25 Needless to say the means for bolting with the hammer could be utilized with any description of fire arm different to that de-

scribed. The bolting piece instead of being in form of a sliding piston, may be of any other shape, for example, that of a pivoting 30 lever, one branch of which is worked by the hammer.

What I claim and desire to secure by Letters Patent of the United States is:—

In an automatic firearm, a breech-block 35 movable rearwardly by the recoil, a barrel movable rearwardly with said breech when bolted to the latter, a catch carried by said barrel, a firing pin having sliding movement in the breech-block, a bolt member mounted 40 in said breech-block and adapted to engage said catch to lock said barrel and breech-block together, said bolt being actuated to locking position by said firing pin upon firing movement of the latter; and means for 45 causing a partial rotation of said barrel to thereby disengage said catch from said bolt when said breech-block has completed a portion only of its recoil movement.

ULDARIQUE AUGUSTE MARGA.
